UNITED STATES PATENT OFFICE.

GEORGE E. MARLATT, OF PASADENA, CALIFORNIA.

TYPOGRAPHICAL DISTRIBUTING BAR.

Application filed November 13, 1926. Serial No. 148,301.

My invention relates to distributing bars of the kind employed for distributing matrices in typographical machines of the linotype class, and has in view the principal purpose of increasing the number of distributing combinations on such bars without increasing the number of ribs from which the distributing combinations are cut. A further object is to provide a bar of laminated construction which may be made by employing economical manufacturing methods.

In the accompanying drawings Figs. 1 and 2 show the complete bar in relation to the channels into which matrices are distributed, Fig. 2 being a continuation of Fig. 1. These figures may be considered as representing either a bar of ordinary type or of my improved laminated type, the type of bar being immaterial so far as the arrangement of the distributing combinations is concerned. Figs. 3, 4 and 5 show three matrices bearing different characters but employing the same combination of distributing teeth, yet capable of distribution to different channels by reason of their different thicknesses. Figs. 6, 7 and 8 are side views of the matrices shown in Figs. 3, 4 and 5. Fig. 9 is a section through a distributor bar of my proposed laminated type. Fig. 10 is a perspective showing a fragment of one of the laminations of Fig. 8. Fig. 11 is a section showing a modified form of laminated bar. Fig. 12 is a horizontal view showing a fragment of the top lamination of Fig. 11.

The established number of longitudinal ribs on the distributor bar is seven, and the number of distributing combinations which may be formed from these seven ribs has heretofore been limited to one hundred twenty-five. The omission in a cross section of the bar of any combination of ribs indicates the retention of a corresponding combination of teeth on the matrix intended to be disengaged from the bar at the point of such cross section. Hence, when the term "distributing combination" is employed herein it will mean a combination of omitted ribs in a cross section of the bar, or a combination of retained teeth on the matrix. It will be understood that the combinations are in duplicate diametrically opposite each other on the two sides of the bar or on the facing sides of the V notch of the matrix, as heretofore. Ordinarily only ninety-one of the possible one hundred twenty-five com-

bination are employed, this having been considered a sufficient number of characters in a single font of matrices. Therefore, I have selected one hundred eighty-two as a sufficient number of combinations for two fonts as an example of the use and possibilities of my distributor bar of increased capacity. But it will appear as the description progresses that the number of combinations may be more or less than one hundred eighty-two and that its employment in connection with two fonts of matrices is not the only use for the improvement. Also, if used in connection with two fonts of matrices, the second font need not follow the first as herein illustrated, but the two fonts may alternate character for character across the length of the distributor bar and magazine; i.e., the first magazine channel might contain a 10-point "e" and the second an 8-point "e", the third a 10-point "t" and the fourth an 8-point "i", etc., the odd-numbered channels containing one font of matrices and the even-numbered channels the other font.

Broadly stated, the principle of my improvement resides in re-employing the regular series of distributing combinations on the bar by making them narrower than heretofore in the instance of their first use and comparatively wider in the instance of their second use. Their first use is in connection with fonts of matrices having narrow distributing teeth and their re-employment is in connection with matrices having comparatively wider distributing teeth. The wider teeth on the matrices of the second font will bridge the bar combinations from which the first font is distributed and therefore the second font will be carried across the first and narrower series of bar combinations and will not be disengaged from the bar until they reach the re-employed but wider bar combinations from which they are intended to be distributed.

The incoming matrices engage the bar as at the left hand end of Fig. 1, being placed and conveyed thereon in any usual or practicable method, such as the usual distributor screws. In the drawings the bar combinations numbered from 1 to 124 are the regular combinations but are narrower than usual, being of a width just sufficient to accommodate the web X¹ (Fig. 6) on which the matrix teeth are usually cut. But in their re-employment beginning with channel No. 106, combination No. 6 (second m) the bar

combinations are as wide as the associated matrix, plus a reasonable clearance, and the matrix teeth are the full width of the thickness of the matrix. Taking this second 5 "m" matrix as an example it will be noted that it bears the same combination as the first "i" (channel No. 6). The combinations numbered from 1 to 5 as well as others there-
beyond are not re-employed for the reason 10 that the matrices bearing these combinations have fewer than three retained teeth and this number is considered essential to with-
stand the tendency of the teeth to wear as the matrices travel across a long distributor 15 bar. This explains the omission of certain numbers in the second series of combination numbers, those retained representing combinations which are the same as those similarly numbered in the case of their first em-
ployment. It will be noted that some of the 20 re-employed combinations beginning with the second m and including the w, fi, fl, ff, ffi, ffl, quad, and others beyond, break into the first series of combinations ending with
25 No. 124. This is because these interrupting characters are thick and it is considered expedient to reserve as many as possible of the regular or first series of combinations for the thinner characters of the second 30 font. By this expedient the regular or first series is "stretched" to reach to channel No. 139, beyond which point all of the matrices of the second font are of sufficient thickness to bridge the combinations in the first series
35 on the bar.

The 182 combinations shown in Figs 1 and 2 does not exhaust the possibilities of re-employment of the combinations. There remain the 40 combinations from No. 85 to No. 40 125 which may be added to the right of Fig. 2 and in addition 27 combinations employing less than three matrix teeth have been omitted from the drawings. With a single exception, the 40 combinations omitted at 45 the end of Fig. 2 are desirable combinations in the sense that they employ three or more matrix teeth.

In addition to the double use of the distributing combinations as above explained, 50 it is also possible to use the same combination three times. For example, in the first "S", second "F" and second "W" channels are shown matrices bearing the same combination of 1st, 3rd and 7th teeth. The "F" 55 will bridge the "S" combination as before explained and by shortening its 3rd tooth (Figs. 2 and 4) on its leading side it will clear an added rib 3^w above its own channel. This added rib will be engaged by the 1st 60 tooth on the "W" matrix and by shortening this 1st tooth on the following side of the matrix, the "W" matrix will be released into its channel at the proper time. In addition a third series of matrices still thicker than 65 the second series would bridge the two series

of bar combinations and the bar could be extended accordingly. The invention would also be useful in connection with an ordinary 90-character font of matrices as a means of increasing the size and strength of the matrix teeth; i. e., the number of teeth could be fewer and larger without increasing the size of the matrix, and the same combinations used in distributing the lower-case matrices could be re-employed for distributing the 75 capital letters.

Referring to the drawings in regard to my improved construction for a distributor bar, it will be noted that the upper, or first, 80 rib is broken up into a great many parts, one part for every other distributing combination; the second rib has only half as many breaks as the first; the third only half as many as the second; the fourth half as many as the third; the fifth, half as many as the fourth; the sixth half as many as the fifth, and the seventh, half as many as the sixth. Since the combinations must be accurately and smoothly cut or chipped one at a time from the ribs in the method heretofore employed, it is apparent that if the more numerous combinations in the first four 85 ribs can be produced by a stamping process or by a milling process several at a time, considerable economy and increased accuracy would result. It is with these objects in view that I provide the laminated construction shown in Fig. 9. The three lower ribs (more or less) are formed as usual on a solid 90 bar A. Since these lower ribs have but few, widely separated combinations, this part of the bar may be constructed in the usual manner or by any improved method made possible by the omission of the upper ribs.

This provides a sufficiently strong and stiff 95 bar to which the laminations B may be secured by means of a series of bolts C or otherwise. Since the four laminations on one side of the bar are the same as those on the other side except for the direction in which they are bent at their lower edges, it follows that 100 in a stamping operation the same tools may be employed for both sides; and in a milling operation many laminations may be milled at one time. Also, in case of wear 105 such as occurs especially at the lower case end of the bar, certain parts of the bar may be renewed as occasion requires. The laminations may be clamped between side plates B¹.

A modified form of laminated bar is illustrated in Fig. 11. In this form the several lower ribs are formed on a solid bar D of sufficient depth to receive the threaded end 115 of a series of bolts E. The laminations F are clamped between the ribbed bar D and a plain bar G, being perforated to receive the bolts E.

Having thus described the advantages and construction of my invention, what I claim 130

as new and desire to secure by Letters Patent, is:

1. A single typographical distributing bar having distributing combinations in duplication, the first of each duplicated combination being narrow and the duplication thereof relatively wider, for the purpose specified.
  2. A distributing bar for typographical matrices having thereon a first series of narrow distributing combinations followed by a second series of relatively wider combinations, in order that the matrices capable of being released from said second series of combinations may be incapable of release from said first series of combinations.
  3. In combination, a distributor bar having a first series of narrow distributing combinations for distributing a first set of matrices having correspondingly narrow distributing combinations a second set of matrices having distributing combinations of a width sufficient to bridge the combinations in said first series of bar combinations, and a second series of distributing combinations on said bar, the combinations in said second series being of a width sufficient to release the matrices in said second set of matrices.
  4. A single distributor bar having thereon a matrix releasing combination of limited width for releasing a matrix having a distributing combination of limited width, and a relatively wider duplicate of said matrix-releasing combination on said bar for releasing a matrix having a distributing combination of corresponding width.
  5. In a matrix-distributing bar, a first series of narrow matrix-releasing combinations and a second series of wide matrix-releasing combinations, said first series of combinations being capable of releasing only matrices having narrow distributing teeth and said second series of combinations being capable of releasing matrices having wide distributing teeth.
  6. In combination, a distributing bar having a matrix-releasing combination cut
- transversely from a series of longitudinal ribs, matrices, having distributing teeth equal in number to the ribs from which said releasing combination is cut, a pair of channels into which said matrices are released, and means whereby the same combination of matrix teeth will release certain matrices into the first one of said pair of channels and others thereof into the other channel, said means comprising a tooth $3^{\frac{1}{2}}$ on said bar, a tooth shortened from one side of the matrices destined for the first of said channels in order to clear said bar tooth in advance thereof, and a tooth shortened from the opposite side of the matrices destined for the second of said pair of channels in order to support said matrices until they reach the second of said pair of channels.
7. A matrix-distributing bar composed of laminations having distributing notches and teeth formed on the lower edge thereof.
8. A matrix-distributing bar composed in part of laminations having distributing notches and teeth formed on the lower edge thereof.
9. A matrix-distributing bar composed of laminations having distributing notches and teeth formed on opposite edges thereof.
10. A matrix-distributing bar composed in part of laminations having distributing notches and teeth formed on opposite edges thereof.
11. In a combination of matrices and matrix-distributing bar having varied matrix-releasing combinations formed from a series of permuted ribs on said bar, means whereby matrices having a certain combination of releasing teeth may be carried beyond a corresponding releasing combination on said bar, said means consisting in making the releasing combination on said matrices of a width sufficient to bridge the corresponding releasing combination on said bar.

Signed at Pasadena, Los Angeles County, California, this 19th day of October, 1926.

GEORGE E. MARLATT.
